UNITED STATES PATENT OFFICE

2,006,513

EXTRACTION APPARATUS

Charles Rascher and Max F. Betzold, Chicago,
Ill., assignors to Rascher & Betzold, Inc., Chicago, Ill., a corporation of Illinois

Application July 20, 1934, Serial No. 736,226

17 Claims. (Cl. 23—259)

The present invention relates to extraction apparatus and has for one of its objects the provision of means whereby one can better control the solvent during the extracting operation and prevent the contamination of the same so that the best results may be obtained.

Another object of this invention is to provide an improved extraction apparatus of the Soxhlet type, comprising a liquid receiving flask for the solvent, an extraction tube and a condenser. In this type of apparatus the material to be treated is placed in the extraction tube and the solvent is placed in the flask. Heat is applied to the flask to vaporize the solvent and the vapors from the solvent enter the extraction tube where they are condensed and fall to the bottom of the tube, the solvent thereafter dissolving out part of the material and carrying the same back to the flask when the liquid solvent is siphoned into the flask in the manner which will be set forth later and which is well understood in the art to which this invention pertains.

Another object of this invention is to provide an improved liquid seal between the flask and the extraction tube including means for readily removing the liquid forming the seal when and if desired, as for instance when one desires to remove the contents of the flask. In the usual type of apparatus of this nature, one tips the flask to remove the contents of the flask and simultaneously remove the liquid forming the seal. Separate receptacles are provided for these and if one is not careful some of the mercury, which is usually used as the sealing fluid, may fall into the receptacle for the contents of the flask with the result that the contents of the flask is contaminated. With our apparatus the mercury seal may be quickly removed before tilting the flask and then the contents of the flask poured into a suitable receptacle.

Another object of this invention is to reduce the fire hazard in apparatus of this nature. A solvent which is inflammable is generally used and in the usual type of liquid seal, some of the condensed solvent vapors are brought into contact with the liquid sealing material and there is a possibility of this being carried to an exposed point of the apparatus. If this occurs and there is an open flame or spark in the vicinity an explosion or fire is apt to result. The solvent will collect on the top of the mercury and when the extraction tube is removed this solvent is naturally exposed. When the extraction tube is again put in place some of this solvent is on exposed portions of the mercury. With our apparatus this

fire hazard is greatly reduced if not practically eliminated.

Another object of this invention is to provide a condenser and extraction apparatus which will not sweat. This is very important for the reason that the moisture thus formed may seep into the solvent or into the extraction tube or fall into the same when handling the various parts of the same as when placing the flask and extractor in operative relation with each other or removing them from their operative positions. Water in the extractor may cause matter to be dissolved out of the material which was not intended to be dissolved out, or the water may form undesirable compounds. Since the tests usually performed with apparatus such as this require the weighing of the residual parts in the extractor and in the flask, the presence of moisture which will disturb the expected results, is very undesirable and it is our object to eliminate this possibility of contamination by providing an improved condenser.

Another object of this invention is to provide means for indicating when and at what rate the cooling fluid is flowing through the condenser.

A still further object of this invention is to provide means for supporting the condenser while the material being treated is being removed from or being placed in the extraction tube, without interrupting the flow of cooling fluid through the condenser. The supporting means also preferably acts to hold the flexible rubber tubes over the glass inlet and outlet conduits of the condenser. This means also makes it unnecessary to remove the flexible outlet tube from the drain pipe and enables the condenser to function even when removed from the extraction tube as will be brought out more fully in the description.

Other objects of this invention will appear as the description of the same proceeds, the novel features, arrangements and combinations being clearly set forth in the specification and the claims thereunto appended.

In the drawing:

Fig. 1 is a front elevation of one embodiment of our invention;

Fig. 2 is a cross-section of the lower part of the device shown in Fig. 1, taken in a vertical plane through the center of the apparatus and parallel to the sheet on which the drawing appears;

Fig. 3 is a cross-section similar to Fig. 2 showing the upper part of the apparatus; and

Fig. 4 is a cross-section taken substantially along the line 4—4 of Fig. 3.

The embodiment shown comprises a flask

in which the solvent is placed, and 11 is an extraction tube of the Soxhlet type, the former resting on the heating plate 12 and the latter being supported in any desired manner as by a 5 clamp on a clamp stand such as is usually used in laboratory work. A cooling fluid such as water is supplied to the condenser 13 of the apparatus from some convenient source such as the water pipe 14, extending in a substantially horizontal 10 position above the apparatus, through the rubber inlet tube 15. The cooling water leaves the condenser through the rubber outlet tube 16.

The extraction tube comprises tube 17 the bottom of which is rounded and has an inlet port 18 and an outlet port 19. The bottom of the tube has a vapor conduit 20 fused to it in alignment 15 with the axis of the tube. The lower end of this conduit is flared outwardly and downwardly to form the skirt 21, and a second skirt 22 is fused 20 to the inner upper portion of the skirt 21 to provide inner and outer skirts for a purpose which 25 will appear later.

A branch vapor conduit 23 leads from the side 30 of the conduit 20 to the inlet port 18. A siphon tube 24 communicates with the outlet port 19 and extends therefrom first upwardly, then downwardly and laterally through the wall of the conduit 20 and has its lower end extending vertically downward substantially centrally of the 35 conduit 20 as is clearly indicated in Fig. 2.

The flask 10 which receives the solvent for the extraction process has a substantially cylindrical mouth portion 25, on the exterior circumferential portion of which there is formed a trough 26, 40 the upper edge 27 of the outer wall thereof being below the lip 28 of the flask. Mercury 26' is placed in this trough and acts as a connecting seal between the flask and extraction tube when the outer skirt is lowered into the mercury as is 45 illustrated in Fig. 2. The vapors formed when the solvent is heated are therefore constrained to move upwardly through the conduits 20 and 23 into the extractor 17 where, after being condensed by their contact with the condenser, the liquid solvent falls to the bottom of the tube 17 onto the material therein. This solvent collects 50 in the bottom of the tube and remains there until the level of the same is high enough to reach the top 29 of the siphon tube 24 at which time the siphon becomes operative to siphon the solvent and dissolved matter back in to the flask 10. This process is carried on as long as desired or necessary, with the solvent periodically siphoning back into the flask where it is re-vaporized 55 and sent again to the extraction chamber.

In the bottom of the extraction chamber is placed a paper thimble 30 or like receptacle for the material to be treated, and this contains a known amount of material to be treated by the 60 solvent. The solvent dissolves out part of this material and carries it down into the flask 10 when the siphoning takes place.

When, for any reason, it is desired to separate the extraction tube and flask, the tube 17 is 65 generally moved upward away from the flask and the flask is then moved laterally away from its position beneath the extraction tube. Any means may be provided for permitting this separation if and when desired. It is during this separation 70 that moisture formed on the exterior of the extraction tube can fall into the flask, but with our apparatus this will not result due to the fact that the condenser we provide prevents the formation of such moisture on the extraction tube. It is 75 also at this time that any of the solvent which

may have collected on the mercury is exposed and may ignite as previously explained.

Before or after raising the tube 17, the mercury can be removed from the trough 26 by means 5 forming an important part of this invention, so that the flask can be emptied readily. This means comprises an integral outlet tube 32 extending downwardly and outwardly from the bottom of the trough, the same being provided with a stopper formed of a solid glass rod 33 about 10 which has been placed a short length of rubber tubing 34 which snugly fits the glass rod. When this stopper is removed the mercury will drain out of the trough and a suitable receptacle can be provided for receiving the same. Thus there 15 is no danger of spilling the mercury into the receptacle for the solvent such as is always present in using extraction apparatus such as that described as prior art.

When the flask is first heated and the hot 20 vapors rise into the conduits 20 and 23, some of the vapors condense on the still cold walls of the conduits and drain back into the flask 10, moving 25 along the inner wall of the inner skirt 22 in so doing. If it were not for the skirt 22 the condensed vapors so formed would drain back along the skirt 21 into the mercury. This, as previously explained, is undesirable due to the fire hazard.

In the top of the extraction tube we place our 30 improved condenser and this is shown particularly in Fig. 3. It comprises a hollow tube 35 having a rounded bottom 36 and a concave top 37, the peripheral edge of which is provided with a downwardly extending lip 37'. A conduit 38 arranged centrally of the tube is fused to and extends 35 through the top 37 and has the outside extension 39 arranged within the lower end of the tube 15, the latter being forced over the extension 39 until the end thereof contacts the top 37. The condenser is also provided with an integral outlet tube 40 received within the upper end of the flexible outlet tube 16, the said end of the latter 40 contacting the top 37 the same as the end of the tube 15.

The cooling water enters the condenser through 45 the flexible tube 15 and conduit 38 and leaves the condenser through the conduit 40 and flexible tube 16. The conduit 38 extends almost to the bottom of the condenser so that the cooling fluid is introduced at a point in the condenser where 50 it will be most effective, namely, adjacent the inlet port 18 of the extraction tube. As the vapors strike the condenser and travel upward along the outside walls of the condenser, the same condense and fall to the bottom of the tube 17 as previously 55 explained.

The top of the condenser is of greater diameter than the mouth of the extraction tube and merely rests on the peripheral lip of the latter, whereby 60 the condenser can be quickly removed. Instead of providing a tight seal between the extraction tube and the condenser as has been done heretofore, we prefer to provide a small vent between the tube 17 and the condenser. This is done in a very simple yet effective manner which is exaggerated somewhat in the drawings for the sake of clearness. The tube 17 has one or more slight depressions 42 in the upper lip portion thereof so that a space is provided between the lip 41 and the top 37 of the condenser. The condenser is held in spaced relation to the inner wall 65 of the extraction tube by means of the small nipples 43 arranged peripherally about the lower end of the condenser tube. This permits the solvent vapors to rise about the sides of the con- 70 75 75

denser so that the vapors are more effectively condensed, and this also prevents the condenser from contacting the inside of the extraction tube to form an area on the extraction tube which is cold enough to cause moisture to form on the outside thereof. The ends of the small nipples are so small that they have very little effect on the temperature of the walls of the extraction tube should the latter be contacted by the nipples. 5
Also since the nipples are solid, the outermost portions thereof will be at a temperature which is above that of the outer walls of the condenser other than the nipples for the simple reason that it takes longer for the heat to transfer through 10 the same. Without the vent between the top of the condenser and the extractor tube it would be difficult for the vapors to rise due to the air pocket which would be present. Furthermore, when the rate of evaporation becomes too great the excess 15 can escape through the vent and the operator on detecting the odor of the escaping solvent, may regulate the apparatus so that it will function properly. Without the vent, a partial vacuum is produced in the extraction flask when the cooled 20 solvent from the extraction tube siphons back into the hot extraction flask. Atmospheric pressure on the outside of the mercury in the trough of the extraction flask then is sufficient to force part of the mercury into the flask. This cannot occur 25 if the pressure within the flask is approximately the same as that outside the flask. Therefore the vent eliminates this danger.

Since the condenser is practically enclosed by the extractor except at the top, the temperature of 30 the extraction tube is more nearly that of the room temperature than is the condenser and therefore there is no tendency for the extraction tube to sweat. The upper side of the condenser is concave so that any moisture which condenses 35 on the top will collect there and not run down over the sides of the extractor or into the same through the joint between the condenser and extractor. As previously explained, the presence of moisture in the condenser is detrimental and we have avoided any possibility of moisture getting into 40 the extractor because of the condenser. If under conditions of extremely high humidity more moisture collects in the concave top of the condenser than the same will hold, it will overflow 45 and the moisture will run over and drip off the lip 37 but will not run into the extractor as it might if the lip were not there. Or a piece of blotting paper placed in the concave top will prevent over-flow. Of course the top of the 50 extractor could be made deeper than shown if desired, but except under extreme conditions, a depth substantially that illustrated will be sufficient.

Since the tubes 15 and 16 are relatively thick, 55 the ends thereof which contact the concave top will cover up a considerable area of the same and thus reduce the amount of moisture which could form. Of course it is obvious that this rubber tubing also prevents the sweating of the glass 60 extension 39 and the glass outlet 40.

A glass ball 44 which is preferably colored in order that it may be seen readily, is arranged in the lower end of the condensing tube 35 and when at rest is only slightly spaced from the 65 lower end of the conduit 38. As the cooling fluid flows out of the lower end of this conduit, the ball is agitated by the same and the amount of agitation depends on the rate of flow of the cooling fluid. Therefore, the amount of agitation indicates in a general way the amount of cooling 70

fluid flowing and the operator soon is able to regulate the flow of cooling fluid even before the heating of the solvent begins.

A wire loop 45, the ends 46 and 47 of which embrace and hold in position the portions of the tubes 15 and 16 which embrace the extension 39 and the outlet conduit 40, not only helps to prevent leakage by having its ends thus arranged, but also serves as a means whereby the condenser may be supported when not arranged in the extractor tube. Thus the loop may be arranged over the handle of the stop cock 48 which regulates the flow of water through the condenser, or a separate hook may be provided for this purpose. This relieves the flexible tube 15 of 10 the weight of the condenser when the extraction tube is removed and makes it unnecessary to remove the tube 15. The lower end of the flexible outlet conduit 16 extends into the waste pipe 49 a distance sufficient to avoid a total withdrawal 15 of the same from the waste pipe when the condenser has been raised and suspended from the handle of said stop cock by the wire loop 45. Therefore, while the material in the extractor is being removed or placed therein, it is not necessary to interrupt the action of the condenser which the operator may have regulated to a nicety to suit the requirements of the process. Thus successive operations of the apparatus do not require re-regulation of the condenser. 20 25

While we do not wish to limit ourselves to the material used for our apparatus, we have found that glass is most satisfactory and all the parts with the exception of the parts 12, 14, 15, 16, 26', 34, 45, 48 and 49 are made of glass. In other words 30 the main parts of the apparatus, namely, the flask, the extractor and the condenser are all glass, thereby making it possible to clean the same more readily as well as prevent any chemical activity which may result from the use of 35 other materials.

Since the outer upper edge of the trough is lower than the lip on the flask, there is little chance for mercury to spill into the flask should the flask be jarred. By preventing the accumulation of solvent in the trough there is no danger of spilling the same when the flask is jarred on removal. In ordinary types of flasks where solvent accumulates, it does so to a marked degree 40 sometimes. This solvent collects in the space between the neck of the flask and the outer skirt (the only one now provided in devices of this nature) and sometimes reaches the top of the flask. The mercury prevents the same from flowing past the lower edge of the skirt, but when 45 the extraction tube is raised, the solvent flows rapidly over the mercury to the outer wall of the trough and will splash over the same. By eliminating this in our invention we have greatly 50 reduced the fire hazard and rendered the instrument more desirable.

Obviously, those skilled in the art to which this invention pertains may make various changes in the arrangement and construction of the parts shown in the drawing without departing from the spirit of this invention, and, therefore, we do not wish to limit ourselves in our invention except as set forth in the appended 55 claims.

Having thus fully described our invention, 60 what we claim and desire to secure by Letters Patent of the United States is:

1. In a device of the class described, the combination with a solvent receiving flask having an open mouth, of an extraction unit having a 65

mouth, the lip of which overlaps the lip of the mouth of said flask, a liquid receiving trough arranged about the overlapping lips of said flask and extraction unit and of sufficient size to receive a sealing liquid to a depth to seal the space between said lips so that the said flask and extraction unit are in sealed communication with each other, and means for draining the sealing liquid from said trough while the parts are in their operative positions with respect to each other.

2. In a device of the class described, the combination with a liquid receiving flask having an open mouth, and a sealing liquid receiving trough arranged circumferentially about said mouth, of an extraction unit having a mouth the lip of which extends into said trough a distance sufficient to be entirely covered by the sealing liquid when the latter is placed in said trough, said trough having a drain opening therein for draining the liquid from said trough, and means for closing said opening.

3. In a device of the class described, the combination with a flask having an open mouth and a trough, U-shaped in cross-section and arranged circumferentially about said mouth, said trough having a drain opening therein at a point near the bottom thereof, of means for closing said opening, and an extraction unit having an open mouth, the edge of which, when said unit and flask are in operative relation with respect to each other, extends into said trough a sufficient distance to be immersed in the sealing liquid when the latter is placed in said trough.

4. A device as set forth in claim 3 in which the extraction unit is provided with a skirt contiguous with the inner wall of said mouth and spaced therefrom, the said skirt extending into said mouth of said flask.

5. In a device of the class described, the combination with a flask having an open mouth, of a trough arranged circumferentially about said mouth and contiguous with the outer wall of said flask for receiving a sealing liquid, an extraction unit having an inlet conduit for receiving vapors from said flask, and at least two skirts contiguous with said inlet conduit and arranged one within the other, the inner one of said skirts extending into the mouth of said flask, and the outer one of said skirts extending into said trough when the extraction unit is in operative relation with respect to said flask.

6. A device as set forth in claim 5 in which said trough has a drain opening therein near the bottom thereof and in which there is provided a means for closing said opening when desired.

7. A flask of the type described comprising a body portion having a mouth, a liquid receiving trough surrounding said mouth having a drain opening therein near the bottom thereof, and means for closing said drain opening.

8. A device of the class described comprising an extraction tube having an inlet conduit, the lower end of which is provided with at least two peripherally extending contiguous skirts one within the other, the said skirts being spaced to receive the lip of an extraction flask, one of said skirts being adapted to be immersed in a liquid seal.

9. In a device of the class described, the combination with a distilling chamber, of an extraction chamber communicating therewith and having an opening therein, a condenser cooperating with and removably supported within said opening, a pair of projecting conduits on said con-

denser, one conduit being the inlet conduit and the other the outlet conduit, a pair of separate flexible conduits, one of which has one end thereof embracing one of said projecting conduits and the other of which has an end embracing the other projecting conduit, and a loop member, the opposite ends of which embrace the said ends of said flexible conduits to hold the same firmly about their respective projecting conduits on said condenser, the said loop also acting as a means whereby the said condenser may be supported by suitable means while out of operative arrangement within said extraction chamber.

10. In a device of the class described the combination with an extractor tube having an opening in the upper side thereof, of a condenser freely supported within said extraction tube through said opening and extending a substantial distance into said tube, a head on said condenser resting on the edge of said opening, the outer periphery of the condenser which lies within said tube being of a smaller outside diameter than the inner diameter of said tube, and means arranged between said condenser and tube for spacing the outer walls of said condenser from the inner wall of said tube.

11. In a device of the class described, the combination with an extraction chamber having an opening in an upper wall thereof, a condenser cooperating with and removably supported within said extraction chamber and extending downwardly into the same through said opening, the condenser having an enlarged head on the upper side thereof the under side of which engages the edge of said opening in said wall, whereby the condenser is supported in operative position within said chamber, said enlarged head having the upper outer side thereof formed with a depression extending substantially to the outer edge of said head for collecting any moisture forming on the upper side of said head to thus prevent the same from running over the outer edge of the head and along the sides thereof into the extraction chamber.

12. A condenser for extraction apparatus and the like comprising a body adapted to be arranged within an extraction chamber and extend through an opening in the upper side thereof, and a head on said condenser adapted to project outside said extraction chamber and having a downwardly extending lip on the periphery thereof of a size to extend beyond the outer supporting edge of said opening in said extraction chamber, whereby moisture forming on the upper side of said head will drain off the same free of the condenser body and the joint formed by the meeting portions of said condenser and said edge of said opening, whereby when the condenser is placed in said extraction chamber with the head protruding above said extraction chamber any moisture dripping from the lip will not flow along the sides of the condenser into the extraction chamber through the aforesaid joint.

13. A device of the class described comprising a condenser body having a transparent portion, an inlet tube leading into said body, the inner side of said body near said inlet tube having a depression, a freely supported movable element in said depression in the path of cooling fluid entering said condenser and normally gravitating into said depression to a position adjacent the end of said inlet tube whereby the force of the cooling fluid flowing into said condenser moves said movable element in a direction upwardly along a side of said depression to indicate the

rate of flow of said cooling fluid through said condenser.

14. In a condenser of the class described, the combination with a tubular body adapted to be arranged with its longitudinal axis vertical when the same is in use, said tubular body having a closed lower end having an inner upwardly forcing concave surface thereon, an inlet tube extending down into said body to a point closely adjacent said bottom, near the lowest point on said concave surface, a freely movable ball resting on said concave surface and gravitating toward said lowest point thereon, the end of said tube being spaced sufficiently from said concave surface to permit said ball to occupy the space therebetween.

15. A condenser of the class described comprising an elongated body portion having a laterally extending shoulder near the upper end thereof adapted to rest on the edge of an opening in an elongated extractor tube of an internal cross-section not substantially larger than the outer cross-section of the condenser, and a plurality of means extending laterally of said condenser having restricted areas for engaging the inner wall of the extractor to hold the outer wall of said condenser spaced from the inner walls of said extractor.

16. In an extraction apparatus, the combina-

tion with an extraction tube having an opening in the upper side thereof of a condenser removably arranged within said tube and extending through said opening, a head on said condenser freely resting on the edge of said opening to support said condenser within said tube, the edge of said opening and adjacent portion on said head being so formed that they are separated at least at one point to permit vapors to escape from said extraction chamber.

17. In a device of the class described, the combination with an extractor having an opening therein, a condenser extending into said extractor and having a laterally projecting means thereon adapted to engage the edge of said opening and support the condenser in operative position, inlet and outlet conduits for said condenser and a drain tube into which the free end of said outlet conduit extends, said outlet conduit being of a length to extend into said drain tube a sufficient distance to prevent total withdrawal of same from said tube upon total withdrawal of said condenser from said extractor, whereby the flow of cooling fluid through said condenser may be continued even when not supported within said condenser.
